TAP CHANGING UNDER LOAD APPARATUS
WITH PARALLELING REACTORS COMMON
TO ALL TAPSLouis C. Aicher, Elm Grove, Wis., assignor to
Allis-Chalmers Manufacturing Company, Milwaukee, Wis.

Application December 21, 1951, Serial No. 262,785

3 Claims. (Cl. 323—43.5)

1

This invention relates to voltage regulating systems including regulating transformers having tap changing apparatus designed for operation while the regulating transformer is under load. The invention is particularly related to improvements in the tap changing circuit for such regulating transformers.

The tap changing under load apparatus of voltage regulating transformers are a considerable factor in the determination of the maximum ratings for which such transformers can be designed. Because the switching apparatus of such tap changers must operate under load there are practical limitations on their current ratings, and these limitations therefore affected the size and rating of the regulating transformers.

The invention hereinafter described comprises a new under load voltage regulating system in which the current rating of the tap changing apparatus is considerably increased independently of the type of regulating transformer or the type of tap changing apparatus associated with the regulator. While the invention is adaptable to and described with relation to regulators embodying dial switch tap changing apparatus, it is not limited to such apparatus.

It is an object of the present invention to provide a circuit for reducing the current carried by the contacts of tap changer apparatus of step type voltage regulators.

Another object of this invention is to provide an improved relatively inexpensive circuit for step type under load voltage regulators having minimum current carried by the individual elements of the tap changing apparatus.

Still another object of this invention is to reduce the cost and number of component parts of a current dividing circuit for the tap changing apparatus of voltage regulators having full and half cycle step regulation.

Objects and advantages other than those above set forth will be apparent from a consideration of the following description when read in connection with the accompanying drawings, in which:

Fig. 1 is a diagram of a circuit for step type voltage regulator embodying this invention, with the regulator shown in a full cycle position; and

Fig. 2 is a diagram of the tap changer in a half cycle position.

The voltage regulator illustrated in the drawing is a step type regulating transformer usable for maintaining the voltage of a load circuit 8, 9 at a constant value independently of changes in the load. In this instance, the regulator includes

2

an exciting winding 11 which has a plurality of spaced taps 12 to 19 and dial type under load tap changing equipment 30 with which the load circuit is regulated by changing the position of load line lead or regulator terminal 9 at the spaced taps of the winding 11. Operation of the dial switch tap changing equipment 30 is accomplished through driving gears 29 by motor 48, which can be caused to operate in either of two directions by a switch 49 connecting the motor to its source 47. Operation of the motor in one direction raises the load voltage, and operation of the motor in the other direction lowers the load voltage. Conventional, automatic control mechanism (not shown) may be provided so that the switch 49 responds to voltage changes of the load circuit.

The dial switch tap changer equipment illustrated includes two pairs of movable contacts, a first pair 33, 34 and a second pair 35, 36. These contacts preferably are all moved substantially simultaneously by a common means including the motor 48 and its gear drive 29.

The dial switch of course includes an insulating board 31 on which are mounted circumferentially spaced fixed contacts 21, 31 and 22, 32. One pair of the movable contacts 35, 36, is shown as being radially spaced from the other pair 33, 34. The fixed contacts are illustrated as being arranged in pairs, such as 21, 22, to provide two sets of fixed contacts which are either radially or axially spaced. Contacts 21, 22 are electrically connected to each other and to tap 14 of the winding. The other pairs of fixed contacts 35 are likewise electrically connected together and to taps of the winding.

Circuit means is provided for the tap changing equipment so that between any two of the movable contacts there is a current dividing means 40 and also so that between the contacts of each pair of movable contacts there is a preventive auto-transformer for effecting the transition from full to half cycle positions and for limiting the circulating current which would otherwise result 45 when the movable contacts are in a half cycle or bridging position.

The circuit means referred to comprises the four movable contacts 33, 34, 35, 36, respectively, which are associated through brushes with collector rings 44, 42, 43, 41. Those collector rings are connected to terminals of two paralleling reactors 55, 56, which places a paralleling reactor between a movable contact of each of the pairs of movable contacts. Movable contact 33 is connected through collector ring 44 and con-

ductor 71 to one terminal of reactor 55, and movable contact 35 is connected through collector ring 43 and conductor 72 to the other terminal of reactor 55. Movable contact 34 is connected through collector ring 42 and conductor 73 to one terminal of reactor 56 and movable contact 36 is connected through collector ring 41 and conductor 74 to the other terminal of reactor 56. Thus, the reactors provide current division between a contact of one pair of movable contacts and a contact of the other pair of movable contacts.

In addition, a current dividing means is provided between the two contacts of each of the pairs of movable contacts. In view of the fact that the pairs of movable contacts must bridge adjacent fixed contacts in every other regulating position, the current division is accomplished in this instance by a single preventive autotransformer 57 which also is utilized to make effective the half cycle positions by preventing the short circuiting of the winding between the bridged taps at a half cycle position of the regulator.

One terminal of the preventive autotransformer 57 is connected to midtap 65 of reactor 55 through circuit breaker 67 and the other terminal of the preventive autotransformer 57 is connected to midtap 66 of reactor 56 through circuit breaker 68. The connection to the midtap of the reactors assures that equal current division will be effected between the movable contacts 33, 35 and 34, 36 by reactors 55 and 56, respectively. In order to provide current division between the contacts of each of the pairs of movable contacts by the preventive autotransformer, it has a midtap which constitutes a terminal 9 of the regulator.

Positive current division between the movable contacts is achieved in either a full or a half cycle position of the regulator. Fig. 1 illustrates a full cycle position in which the regulator terminal is connected to the midtap of the preventive autotransformer so that the load current divides equally between the two halves of that autotransformer and at the midtaps of reactors 55, 56. Each of those midtapped reactors provides equal parallel current division between the movable contacts through parallel circuits.

In the half cycle position shown in Fig. 2 the autotransformer and the reactors also effect current division of one-fourth load current in each of the movable contacts in the same manner as for the full cycle position since the arrangement of the midtapped reactors is not altered.

Since a circuit arranged according to this invention for under load regulators includes only a single preventive autotransformer, a single set of circuit breakers and only one pair of parallel reactors, the cost of doubling the rating of the regulator is relatively low.

Although but one embodiment of the present invention has been illustrated and described, it will be apparent to one skilled in the art that various changes and modifications may be made therein without departing from the spirit of the invention or from the scope of the appended claims.

It is claimed and desired to secure by Letters Patent:

1. A voltage regulating system comprising a

winding having a plurality of fixed contacts, a first pair of movable contacts, a second pair of movable contacts, a first reactor, a second reactor, and a preventive autotransformer, one contact of said first pair of movable contacts connected to one terminal of said first reactor and one contact of said second pair of movable contacts connected to the other terminal of said first reactor, the other contact of said first pair of movable contacts connected to one terminal of said second reactor and the other contact of said second pair of movable contacts connected to the other terminal of said second reactor, one terminal of said autotransformer connected to the midtap of said first reactor and the other terminal of said autotransformer connected to the midtap of said second reactor, the midtap of said autotransformer constituting a terminal of said system.

2. A voltage regulating system comprising a winding having a plurality of spaced fixed contacts, a first pair of spaced movable contacts, a second pair of spaced movable contacts, means for moving said movable contacts across said fixed contacts, each of said pairs of contacts cooperating with said fixed contacts to provide full and half cycle switch positions, a first reactor, a second reactor, and a preventive autotransformer, one contact of said first pair of movable contacts connected to one terminal of said first reactor and one contact of said second pair of movable contacts connected to the other terminal of said first reactor, the other contact of said first pair of movable contacts connected to one terminal of said second reactor and the other contact of said second pair of movable contacts connected to the other terminal of said second reactor, said preventive autotransformer providing current dividing means between the movable contacts and effecting the transition from full to half cycle regulating positions by having one of its terminals connected to the midtap of said first reactor and the other of its terminals connected to the midtap of said second reactor and having its midtap constituting a terminal of said system.

3. A voltage regulating system comprising a transformer with a winding having a plurality of taps and tap changing apparatus including first and second pairs of movable contacts, a plurality of fixed contacts, a terminal of said system, and a plurality of midtapped reactors connected between said movable contacts and said terminal, the midtap of a first of said reactors constituting said terminal, the midtap of a second of said reactors connected to one terminal of said first reactor and the midtap of a third of said reactors connected to the other terminal of said first reactor, the four contacts of said first and second pairs movable contacts severally connected to the four terminals of said second and third reactors, said fixed contacts severally connected to said taps, and means for substantially simultaneously moving said movable contacts across said fixed contacts to change the position of said terminal with respect to said taps.
